FIG. 8.

UNITED STATES PATENT OFFICE.

ERIK G. TORNKVIST, OF NEW YORK, N. Y.

UNIVERSAL SAFETY RAZOR.

Application filed May 11, 1926. Serial No. 108,309.

This invention relates to safety razors of the self stropping class, and more especially to those wherein the blade shield is removable to permit insertion of a strop, and whose handle is shiftable to a second position to manipulate the blade when stropping the same.

The main purpose of my invention is to produce a razor having all the advantages of safety razors in general, and in addition that of having a positive and effective means for stropping the blade thereof without using any auxiliary appliances other than a strop.

Another object is to provide a razor of this type with an effective blade guard which is adjustable to provide for wear on the blade occasioned by stropping and prolonged use.

Other objects and the various advantages accruing from the novel features of the invention will appear herein as the specification proceeds.

In the drawing forming part hereof;

Fig. 1 is a view of a device made according to my invention and embodying the same.

Fig. 2 is a side view of the same.

Fig. 3 is another side view of the same with parts in altered positions.

Fig. 4 is a view of the device when used on a strop, and having the handle in a new position.

Fig. 5 is a view of the blade grip with its frame and a blade.

Fig. 6 is a bottom view of the same frame.

Fig. 7 is a view of the blade guard of the first three views.

Fig. 8 is a rear edge view of the guard mentioned.

Fig. 9 is a view of the same from one end.

Fig. 10 is a longitudinal section of the blade grip and its core shown in the first five views.

Throughout the views, the same reference numerals indicate the same or duplicate parts.

In the use of safety razors it is the common experience that blades must frequently be renewed, and as this is an item of expense, various additional devices have been proposed for rehoning and resharpening the used blades. However the need has been felt for a self contained razor which can both be honed as well as stropped without extraneous devices. This invention is designed with this thought and the previously mentioned purposes in mind, and in practice, a

handle 1 is adapted to screw into the aperture 22 of a frame 13 which has a pair of similar lugs 2 and 3.

A shaft 9 projects through these lugs and in either extremity is a threaded aperture noted 11, which is adapted to receive the handle 1 when disengaged from aperture 22. The shaft has a blade grip 8 folded about the same and soldered or welded thereto, and acts as an interior limit for blade 10 which may be inserted between the opposite halves of grip 8. The blade is preferably hollow ground, both in order to render it easier to sharpen and also to have its inner portion heavier and easily retained. The grip has at one extremity a slightly bent or rounded edge at 18 to act as a stop for the blade, while the other has a similar edge at 19, which, however may expand a little as a spring by virtue of the cut away section at 20. The blade may thus be slid out or into position at this end of the grip, and the spring edge 19 will tend to snap into position behind the blade and retain it.

The frame has a dovetail block 21 secured beneath the same, and the handle normally screws up toward the same when the device is to be used as an ordinary safety razor. But a guard 23 may be interposed beneath the frame and may straddle the handle by virtue of its open slot at 24. The slot is actually located in a plate 7 attached to the guard, and the latter has a corresponding larger dovetail slot 25 which is adapted to fit snugly outside block 21 of the frame. Naturally if this guard is placed in position under the frame and the handle screwed into place, the latter will grip the edges of plate 7 and wedge the same up against block 21 and thus hold the guard in position.

The guard has a series of teeth as noted at 6 as is customary in this class of devices, but the two extreme teeth are made in the form of hooks or blade retainers at 4 and 5, while the latter are rearwardly buttressed by a pair of inclines 14 and 12 which serve in addition to support the blade when normally held in the retainers.

If the handle is slightly unscrewed, the guard may be drawn out of engagement, as initially indicated in Fig. 3 and entirely removed, when it is desired to hone and strop the blade. The handle may then be completely removed and inserted into one end of shaft 9 and screwed up tight. It is now temporarily a unit with the shaft and blade

grip, and also with the blade which can therefore be completely controlled by the handle. The blade may be laid on a hone and pushed along the same by means of the handle, then turned over and similarly drawn over the stone until the desired result is attained, the only point needing attention being the frame 13 which may be kept out of the way at each stroke by giving the handle a toss each time. This operation is so obvious and accessible as to require no illustration, especially as this point is partly used in stropping, which operation is shown in Fig. 4.

15 Here, the strop is passed under the grip and above the lower edge of the frame, so that the strop is captive during the stropping operation. It is but necessary to turn the handle until the blade lies on the strop, when 20 the blade may be drawn backward along the strop like any ordinary razor, after which the handle may again be turned the other way to lay the blade with its other side on the strop and the device drawn in 25 the other direction.

This turning of the handle and drawing the blade along the strop may be repeated until the blade is sharp, and is easily and directly under control at all times. More- 30 over, the pressure of the blade on the strop is also a point directly controlled at will.

When the blade is sufficiently stropped, the guard may be mounted beneath the frame on block 21, the blade dropped into position 35 on the inclines 12 and 14, after which the guard may be pushed on until the blade stops the retainers 4 and 5. The handle may now be released and secured to the lower part of the frame and screwed up tight.

40 This again assembles the whole into a unit.

The frame may be made of suitable metal and in any suitable size, naturally, and I may alter it to the extent of having a handle aperture in only one end of the grip shaft

45 9. In fact, one end may be enlarged as indicated at 16 and may have a very large handle seat as indicated at 17.

Various modifications of this nature may be made without departing from the spirit 50 of my invention, and I therefore reserve the same as part thereof.

Having now fully described my invention, I claim:

1. A razor comprising a frame, a hingedly disposed blade grip in the same, a blade in said grip, a handle adapted to be attached to said frame and a second attachment seat for said handle upon said grip.

2. A razor comprising a frame having a 60 pair of similar lugs, a shaft projecting through said lugs and a blade grip secured to said shaft, a blade adapted to be secured in said grip and a handle adapted to be attached to said shaft.

65 3. A razor comprising a frame having a

bridge member provided with a dovetail projection, a plate member adapted to fit snugly about said projection and be relatively located to the bridge member thereby, a handle adapted to be secured to said projection and 70 wedge said plate member against the projection, a blade grip mounted upon said frame and provided with a blade and a plurality of guard teeth on said plate member.

4. A razor comprising a frame having a 75 projection thereon and a blade grip mounted therein, a handle adapted to be secured to said projection and a guard plate having a series of guard teeth adjacent to said blade and adapted to straddle said handle and 80 said frame projection.

5. A razor including a frame comprising a bridge member having a pair of similar lugs, a shaft provided with a blade suspended between the same, a slidible guard having a 85 row of teeth normally adjacent the edge of said blade and adapted to be rigidly secured to said bridge member, and means to frictionally secure said guard to the bridge member including a handle adapted to be secured to said member.

6. A razor including a frame comprising a bridge member terminating at the extremities in a pair of spaced lugs, a shaft connecting said lugs and having a handle seat upon 95 one extremity, a blade adapted to be secured to said shaft, a second shaft seat beneath said bridge member, a handle attachable to said shaft seat or said bridge seat, and a toothed guard adapted to straddle said handle beneath said bridge member and to be secured to said bridge member by tightly seating said handle into said bridge.

7. A razor including a frame comprising a bridge member and a rotatable member 105 mounted above said bridge terminating beyond the same at one extremity in a handle whereby to manipulate said rotatable member, a blade adapted to be secured to said last member, and a guard for said blade 110 adapted for direct attachment to said bridge member.

8. A razor including a frame member comprising a bridge having a pair of lugs spaced apart, a rotatable member passing 115 through said lugs and terminating at one extremity in a handle whereby to manipulate said rotatable member, and a blade adapted to be secured to said last member between said lugs.

9. A razor including a frame comprising a bridge member having a pair of spaced lugs inclined away from one edge thereof over the other edge of the same, a blade adapted to be mounted between said lugs and 125 adapted to swing therebetween, and a handle adapted to be connected to said blade whereby to move the same.

10. In a razor having a bridge member and a blade mounted above the same, a guard 130

adapted for attachment to said bridge member comprising a plate having a row of teeth along one edge thereof and an incline at each extremity to reinforce the two extreme blade stops on said inclines, a plate secured upon the under side of said first plate, there being a dovetail slot opening from one edge in said second plate and a second slot in the edge of said first plate to correspond with said dovetail slot, and a handle adapted to pass through said slots to said bridge.

Signed at 132 Nassau Street, in the borough of Manhattan, city and State of New York this 7th day of May, 1926.

ERIK G. TÖRNKVIST.
